UNITED STATES PATENT OFFICE

2,578,127

EARTH TERRACER WITH VARIABLE-SPEED
TRANSMISSIONEdgar V. Collins, Ames, Iowa, assignor to Iowa
State College Research Foundation, Ames, Iowa,
a corporation of Iowa

Application January 15, 1945, Serial No. 572,854

5 Claims. (Cl. 97—43)

1

This invention relates to drive units for soil moving machines and more particularly to infinitely variable drive units of the V-belt type.

One of the objects of the invention is to provide a variable drive unit which is light in weight which includes a minimum number of parts and which provides a wide range of driving ratios.

Another object is to provide a drive unit which can easily be mounted on a soil moving machine and can easily and quickly be adjusted to vary the operation of the machine.

Still another object is to provide a variable drive unit of the V-belt type in which a single variable pulley is employed and in which the pulley centers are maintained in the same plane under all operating conditions.

A further object is to provide a variable drive unit which is controlled by simultaneous movement of the pulleys toward and away from each other and the opening or closing of one of the pulleys.

These and other features of the invention will be seen from the following detailed specification read in connection with the accompanying drawings forming part thereof and in which—

Figure 1 is a side elevation with parts in section of a soil moving machine embodying the invention;

Figure 2 is a partial plan view of Figure 1; and

Figure 3 is an enlarged partial section on the line 3—3 of Figure 1.

The soil moving machine, as illustrated, is of the type more particularly described and claimed in my Patent No. 2,063,584. As shown, the machine includes a frame indicated generally at 10 which is connected to cross frame members 11 at the rear end of the machine. The frame supports a plow bottom 12 substantially like a conventional moldboard plow with the moldboard cut off at the back. Adjacent the back of the plow bottom a rotatable soil throwing member 13 is supported by the frame and is formed with a helical thread 14 thereon. The soil throwing member receives soil backed up by the plow bottom and throws it laterally as is fully described in my Patent No. 2,063,584.

The machine may be mounted on and operated by any desired type of tractor illustrated as including a gear box 15 supported on driving wheels 16. The frame 10 is connected to the gear box by a pair of laterally spaced bottom links 17 pivoted to the frame and the gear box and a central top link 18 similarly pivoted to the frame and the gear box. This linkage supports the frame on the tractor to permit vertical

2

movements thereof which may be controlled through control mechanism on the tractor, not shown. The soil throwing member is adapted to be driven from the tractor by a power take-off shaft 19, driven from the tractor engine. The shaft 19 is connected through a universal joint 21 to a horizontal shaft 22 in a beveled gear drive unit, indicated generally at 23. The shaft 22 carries a bevel gear within the unit 23 which meshes with a bevel gear on a vertical shaft 24 lying parallel to the soil throwing member 13.

The bevel gear unit 23 is mounted for movement transversely across the frame members 11 and is guided during such movement by pins 25 on the unit 23 which slidably fit in slots 26 in the frame members 11. As best seen in Figure 3, the slots 26 slope downwardly toward the soil throwing member 13 so that the bevel gear unit will move slightly downward as it approaches the soil throwing unit. The shaft 24 slidably carries a collar 27 having pins on its opposite sides riding on an upwardly sloping cam surface 28 on the plates 11. The pins 25 and the pins on the collar 27 are connected by links 29 to a cross head member 31 guided in slots 32 in the frame plates 11. The construction is such that the links 29 will hold the bevel gear unit 23 against twisting or tilting as it is moved toward and away from the soil throwing member. In the foregoing, the inclined slots 26 serve as cams and the pins cooperate therewith in guiding the bevel gear unit for movement toward and away from the soil throwing member. Any desired type of mechanism may be used to move the head 31 but, as shown, it is connected to a screw 33 threaded in a plate 34 which is secured to the frame. The screw may be turned by a handle 35 to move the gear unit to any desired position.

The shaft 24 of the gear unit has rigidly secured to its upper end a V-pulley part 36 and a complementary pulley part 37 is connected to the collar 27 for movement axially toward and away from the part 36. The V-pulley 38 is rigidly secured to the upper end of the soil throwing member 13 and a V-belt 39 drivably connects the two pulleys.

With this construction as the gear unit 23 is moved toward the soil throwing member 13, the gear unit will be moved downwardly to move the pulley part 36 downwardly. At the same time the cam surfaces 28 will raise the collar 27 to raise the pulley part 37, thereby reducing the space between the parts 36 and 37. This action will squeeze the belt 39 peripherally outward of the pulley parts to increase the effective diameter of

the driving pulley, thereby to turn the soil throwing member at a higher rate of speed. Movement of the gear unit away from the soil throwing member will cause the pulley parts 36 and 37 to separate, thereby reducing their effective pulley diameter and reducing the speed of rotation of the soil throwing member. By properly shaping the slots 26 and the cam surfaces 28, the overall belt length around the two pulleys may be maintained constant and the pulleys may be held in the same operative plane. With this construction a very simple and infinitely variable ratio is provided between the drive unit and the soil throwing member which can easily and simply be adjusted during operation of the machine.

While the drive mechanism has been described in connection with a soil moving machine to which it has particular application, it will be understood that this unit might be employed to advantage in various other environments. It will also be apparent that various structural changes might be made in the mechanism without departing from the spirit or scope of the invention and that the embodiment illustrated is not to be taken as a definition of the limits of the invention, reference being had for this purpose to the appended claims.

What is claimed is:

1. In combination with a soil moving machine having a frame, a soil cutting and elevating member on the frame, and a rotatable soil throwing member mounted on the frame in position to receive soil directed thereon by said soil cutting and elevating member, a drive unit for the soil throwing member comprising a bevel gear equipped shaft and a housing support therefor movably mounted on the frame for movement toward and away from the soil throwing member, a V-pulley on the bevel gear shaft formed with axially separable parts to provide a variable ratio, a fixed V-pulley on the soil throwing member, a V-belt connecting the pulleys, a lever adapted to move the bevel gear shaft toward and away from the soil throwing member, and a cam member carried by said frame and engaging supports for at least one of the parts of the first named pulley to vary the separation thereof as the bevel gear mechanism is moved.

2. In combination with a soil moving machine having a frame, a soil cutting and elevating member on the frame, and a rotatable soil throwing member mounted on the frame in a position to receive soil directed thereon by said soil cutting and elevating member, a drive unit for the soil throwing member comprising a bevel gear unit mounted on the frame for movement toward and away from the soil throwing member and including a shaft parallel to the axis of the soil throwing member, cooperating cam and pin members on the frame and bevel gear unit respectively to guide the bevel gear unit at an angle to the shaft as it moves toward and away from the soil throwing unit, a lever for moving the bevel gear unit and shaft toward and away from said soil throwing unit, a V-pulley part rigidly connected to the shaft, a second V-pulley part movable toward and away from the first named V-pulley part to provide a variable drive ratio, cam means cooperating with the second V-pulley part to move it as the bevel gear mechanism is moved, a V-pulley on the soil throwing member, and a V-belt connecting the V-pulleys.

3. In combination with a soil-moving machine having a frame, a rotatable soil-throwing member mounted on the frame, a drive unit for the soil-throwing member comprising a bevel gear unit mounted on the frame and including a shaft parallel to the axis of the soil-throwing member, cooperating cam and pin members on said frame and bevel gear unit for guiding said bevel gear unit for movement toward and away from the soil-throwing member, lever means for moving said bevel gear unit whereby in response to said cam and gear members the unit is moved toward and away from the soil-throwing member, a V-pulley rigidly connected to the top portion of the soil-throwing unit, a second V-pulley mounted upon the shaft of said bevel gear unit, said second V-pulley comprising a pair of pulley parts at least one of which is movable with respect to the other, and a V-belt connecting the V-pulleys.

4. In combination with a soil moving machine having a frame, a soil cutting and elevating member on the frame, and a rotatable soil throwing member mounted on the frame in a position to receive soil directed thereon by said soil cutting and elevating member, a drive unit for the soil throwing member comprising a bevel gear mechanism having a shaft lying substantially parallel to the axis of the soil throwing member, a V-pulley on the shaft, a V-pulley on the soil throwing member, a V-belt drivably connecting the pulleys, one of the V-pulleys being formed of axially separable parts to vary the driving ratio and being movable toward and away from the other pulley, and a lever connected to one of said separable pulley parts and movable to shift said part relative to the other.

5. In combination with a soil moving machine having a frame, a soil cutting and elevating member on the frame, and a rotatable soil throwing member mounted on the frame in a position to receive soil directed thereon by said soil cutting and elevating member, a drive unit for the soil throwing member comprising a bevel gear-equipped shaft and a housing support therefor movably mounted on the frame for movement toward and away from the soil throwing member, a V-pulley on the bevel gear shaft formed with axially operable parts to provide a variable ratio, a fixed V-pulley on the soil-throwing member, a V-belt connecting the pulleys, and a lever connected to said bevel gear housing support to shift said support relative to the soil throwing member and connected also to one of said separable pulley parts to shift said part relative to the other.
